UNITED STATES PATENT OFFICE.

HERMANN SEUFERT, OF BROOKLYN, NEW YORK.

FILM-FEEDING MECHANISM FOR CINEMATOGRAPHS.

Application filed November 2, 1922. Serial No. 598,481.

To all whom it may concern:

Be it known that I, HERMANN SEUFERT, a citizen of the United States of America, residing at Brooklyn, in the county of Kings 5 and State of New York, have invented certain new and useful Improvements in Film-Feeding Mechanism for Cinematographs, of which the following is a specification.

In cinematographic machines, the apparatus for feeding the film bands, as hitherto constructed, have the drawback that the so-called "dark period" or the time during which the film is advanced is comparatively too long or if that time by some mechanism 15 is shortened, this takes place at the cost of a very rapid wear of the feeding mechanism.

One object of this invention is to provide means which will considerably shorten the 20 "dark periods" and minimize the wear of the whole mechanism.

Another object is to provide means for reducing the noise caused by the moving parts of the machine.

25 The invention will be clearly and fully understood by reference to the accompanying drawing in which similar reference characters denote corresponding parts and in which Fig. 1 is a section on line 1—1 of 30 Fig. 2 showing the feeding mechanism enclosed in a casing to render it noiseless and Fig. 2 is a section on the broken line 2—2 of Fig. 1.

In the accompanying drawing only so 35 much of the cinematograph machine is shown as is necessary to understand the subject matter of the present invention.

10 denotes a casing composed of sections 10¹, 10² and 10³, the latter serving as a base 40 and 10² as a front cover for the box shaped section 10¹. These sections when tightly joined together after the parts to be herein-after described are assembled, form a box in which the noise of the moving parts of 45 the mechanism is muffled.

Rotatively mounted in the casing 10 on a fixed horizontal axle 11 is a hollow drum 12 which at one end is formed with a removable lid 13 and at the opposite end has fixed 50 to it or is formed integrally with a gear 14. This gear is adapted to mesh with a pinion 15 keyed to the spindle 16 carrying the fly wheel 17 and which may be driven from a motor (not shown) or otherwise. Projecting inwardly into the drum from the rear wall thereof are a plurality of equidistantly

arranged projections 18 (four in the present example) on which are slidably mounted catches or pins 19, the rear ends 19' of which are in form of sleeves slidably bearing on 60 said projections 18. The forward ends of said pins 19 are slidably guided in sockets 13' formed in the cover 13 of the drum. Each of these slidable pins carries a fixed cross pin 20 on which is rotatively mounted a 65 roller 21. Keyed to the fixed axle 11 of the drum is a disk 22 formed with a cam portion 23 facing and cooperating with said rollers 21. The pins are actuated by springs 24 mounted around the projections 18 so that the rollers 21 will be held in frictional contact with the cam bearing surface of the disk 22. When during the rotation of the drum 12 said rollers 21 arrive opposite the cam portion 23, the latter will permit the 70 pins 19 to be thrust forwardly under the action of the springs 24. Rotatively mounted on the axle 11 in proximity to the lid 13 of the drum 12 is also a disk 25, which is formed with a circular series of equidistantly 75 arranged perforations 26 capable of engaging the free ends of the pins 19 when projected forwardly, as aforesaid, under the action of the springs 24. The distance between the individual pins 19 and that between adjoining perforations 26 conform 80 with the length of a film picture. Consequently during the rotation of the drum 12, the movable pins 19 will successively enter the perforations 26 and feed the disk 25 a 85 fraction of rotation conforming with the length of a picture. This rotation will be transmitted to the feed roller (not shown) mounted on the spindle 27 through the medium of a gear 28 operatively connected to 90 the disk 25 and meshing with a pinion 29 mounted on said spindle 27.

In the present example the gear 28 is fixed on a sleeve like extension 25' of the hub of the disk 25 which is rotatively mounted in 100 the lid section 10² of the casing. In practice the gear 28 and pinion 29 are also arranged within the casing instead of outside, so that their movements also may be noiseless.

The film guide rollers (not shown) which are adapted to be mounted on the spindles 30, 31 receive motion from the driven spindle 16 through the gears 32, 33, 34, 35 and 36 in the usual manner.

What I claim is:

1. In a film feeding mechanism for a cine-

- matograph, the combination with the spindle for the film feed roller, of a continuously revolving closed drum, a set of catch members and a cam in said drum, said cam being adapted to actuate said catch members and means operatively connected to said spindle and adapted to be successively revolved by said catch members to feed the film each time the length of a picture.
2. In a film feeding mechanism for a cinematograph, the combination with the spindle for the film feed roller, of a continuously revolving hollow drum, a set of equidistantly arranged catch members carried by and projecting inwardly from said drum, a cam member inside said drum and adapted to intermittently actuate said catch members and means operatively connected to said spindle and adapted to be successively revolved by said catch members to feed the film each time the length of a picture.

3. In a film feeding mechanism for a cinematograph, the combination with the spindle for the film feed roller, of a continuously revolving hollow drum, a set of equidistantly arranged resilient catch members carried by and projecting inwardly from said drum, a cam member inside said drum adapted to intermittently actuate said catch members, means operatively connected to said spindle and adapted to be successively revolved by said catch members to feed the film each time the length of a picture, and a tightly closed casing enclosing the aforesaid parts to muffle the noise thereof during operation.

In testimony whereof I affix my signature in presence of two witnesses.

Hermann Seufert.
